UNITED STATES PATENT OFFICE.

JOHN PONCHOR, OF EAST ST. KILDA, VICTORIA, AUSTRALIA.

FURNACE.

1,137,420.

Specification of Letters Patent. Patented Apr. 27, 1915.

Application filed July 13, 1912. Serial No. 706,929.

To all whom it may concern:

Be it known that I, John Ponchor, a subject of the King of Great Britain, residing at East St. Kilda, in the State of Victoria, Australia, have invented certain new and useful Improvements in Furnaces; and I do hereby declare the following to be a full, clear, and exact description of the invention, such as will enable others skilled in the art to which it appertains to make and use the same.

My invention relates to boiler fire boxes, furnaces, and analogous fuel burning devices, and has for its object to provide means for rendering the combustion which takes place therein, complete, thereby effecting economy in the use of fuel and an abatement of the smoke nuisance.

Particularly, the invention relates to the provision of such means in connection with low pressure boilers, such as used for heating purposes.

To such ends, generally stated, the invention consists of the novel devices and combinations of devices hereinafter described and defined in the claims.

In my pending application Serial Number 706,977, entitled "Process of obtaining complete combustion," and filed of date July 1st, 1912, I disclose and claim a novel process of effecting complete combustion and the elimination of smoke from the products of combustion, and the present invention illustrates one form of apparatus, by means of which the said process will be carried out. My present invention is particularly directed to the provision of an apparatus for carrying out the said improved process in connection with a low pressure boiler used for heating purposes. The said process requires steam under quite high pressure, to-wit, the pressure should be somewhere around thirty pounds, or more, whereas, in these low pressure boilers used for heating purposes, the steam pressure is frequently carried as low as two or three pounds, or even lower. Hence, in accordance with my present invention, I employ an auxiliary steam generator in connection with the furnace, or boiler fire box, to supply the steam under the required relatively high pressure. Also, as an additional important feature, I so arrange this auxiliary heater so that any surplus steam, to-wit, steam not required to facilitate or increase the combustion, and thereby burn up or eliminate the smoke, is

delivered into the boiler of the main heating plant.

In the accompanying drawings which illustrate the invention in its preferred form, like characters indicate like parts throughout the several views.

Referring to the drawings, Figure 1 is a view partly in elevation and partly in transverse vertical section showing my present invention installed in connection with the boiler and box of an ordinary steam heating plant; Fig. 2 is a detail view in elevation, looking at one end of the bridge of the fire box; Fig. 3 is a section taken approximately on the line $x^a x^b$ on Fig. 1, some parts being broken away; Fig. 4 is a detail view in elevation showing the so-called nozzle pipe, and means for adjusting the same, some parts being broken away; Fig. 5 is a detail in horizontal section on the line $x^c x^d$ on Fig. 2, some parts being broken away; and Figs. 6 and 7 are detail views in elevation showing modified forms of the construction illustrated in detail in Fig. 5.

Of the parts of the heating plant, the numeral 1 indicates the walls of the fire box, the numeral 2 the boiler, and the numeral 3 the grates. The rear ends of the grates 3 rest upon bearing blocks 4 that are preferably secured, detachably, by dove-tailed flanges 5 to the lower ends of the bridge forming bars 6. These bridge forming bars 6 are detachably seated on the base 7 and are interlocked to the flanges 8 thereof. The vertical portions of the bridge bars are placed in close contact so as to form a practically solid wall extending above the fuel line, but their arched upper ends are reduced in width at 6^a and thereby laterally spaced, so as to afford a multiplicity of passages. The ends of the arched portions 6^a rest upon and are interlocked with a vertical rear wall 9 of the base 7.

The auxiliary steam generator, as shown, comprises a relatively small upright boiler 10, conveniently supported by brackets 11 on one side of the brick work 1. Within the fire box, preferably, at one side thereof, and extending above the grates, is a steam generating manifold made up of vertical water tubes 12, a horizontal lower tube 13 and an inclined or oblique upper tube 13^a. One end of the lower tube 13 is connected by a pipe 14 to the lower portion of the auxiliary boiler 10 and the upper end of the oblique tube 13^a is connected by a pipe 15 to the in-

termmediate portion of the said boiler 10 at a point somewhat below the water level line y (see Fig. 1).

The numeral 16 indicates a normally closed drain pipe, which, as shown, is extended from one end of the lower manifold pipe 13. The said manifold constitutes one of a large number of different steam generators that may be employed. It is evident that steam generated in the manifold will pass upward into the oblique pipe 18 and from thence through the pipe 15 into the auxiliary boiler 10. By the oblique arrangement of the said tube 13, steam pockets within the generator are avoided. The relatively cold water from the boiler 10 is delivered through the pipe 14 into the generating manifold; so that a continuous circulation of the water in the boiler 10 is maintained.

Preferably, the water is supplied to the boiler 10 through an automatic valve which maintains the constant desired level. As shown, the water is supplied from a pipe 17 which connects to the casing 18 of an automatic float controlled water inlet valve of suitable construction. As shown, the said valve is provided within, with a float 19 connected to an intermediately pivoted lever 20, the free end of which carries a valve 21 that closes the upper end of the pipe 17 whenever, and only when, the float 19 is raised by water accumulated in the boiler 10 at the altitude indicated by the broken line marked y on Fig. 1. The valve casing 18 is connected to the upper and lower portions of the boiler 10, respectively, by pipes 22 and 23. The water will flow from the casing 18 into the boiler 10 through the lower pipe 23, but the upper pipe 22 gives an equalization of pressures within the said valve casing. The pipes 17 and 23 are shown as connected by a branch 24 having a normally closed valve, the only purpose of which is to provide means whereby, in testing out the pipes and joints of the apparatus, water may be forced entirely through the connections thereof, by opening the valve of the said connection 24.

Located within the air bridge formed by the bars 6 and coöperating wall 9 is a so-called nozzle pipe for delivering the steam into the burning products of combustion from the fuel within the fire box or furnace. This nozzle pipe 25 is shown as supported by arms 26 of a rock shaft 27 journaled in suitable bearings 28 secured in the base 7. Preferably, means is provided for oscillating the shaft 27, and hence, for locking the nozzle pipe 25, from the exterior of the furnace, and, as shown, the shaft 27 is provided with a bevel gear 29 (see Fig. 4), that meshes with the bevel gear 30 on the upper end of a shaft 31, journaled in suitable bearings on the base 7 and provided at its lower

end (see Fig. 2) with a bevel gear 32 that meshes with a bevel gear 33 of an operating rod 34 having at one end an operating crank 35 located at the exterior of the brickwork 1.

The numeral 36 indicates a steam delivery pipe, the upper end of which is connected to the tube of the boiler 10, the lower portion of which is extended horizontally into the fire box below and at the rear of the grates, and from thence is extended upward and connected to the down-turned end 25^a of the nozzle pipe 25 by a swivel joint connection 37, preferably of the ball and socket type, the axis of which is located for alinement with the axis of the rock shaft 27. At its other end, the nozzle pipe 25 is normally closed. In its upper portion, the nozzle pipe 25 is provided with a multiplicity of very small perforations 38, through which the steam will be discharged into the products of combustion or burning gases from the fuel which is burning within the fire box. These steam discharge passages 38 should not be over $\frac{1}{2}$ of an inch in diameter.

Different furnaces or fire boxes have grates of different types, and the bearing blocks 4 which are interchangeably usable with the bridge bars 6, should have upper faces of different contour to fit the ends of the grate bars. In the construction best illustrated in Fig. 2, the upper faces of the bearing blocks 4 are beveled but straight. In the construction illustrated in Fig. 6, the upper faces of the bearing blocks 4 are horizontal and flat, but in the construction shown in Fig. 7, the upper faces of the bearing blocks 4 have V-shaped notches that receive V-shaped lugs 3^a of the grate bars 3.

A secondary steam delivery pipe 36^a extends from the main or primary steam delivery pipe 36 into the upper portion of the main boiler 2. The numeral 39 indicates a gravity closed blow-off or safety valve, which, as shown, is located at the junction of the pipes 36 and 36^a. The numeral 40 indicates a yieldingly closed valve that normally closes the pipe 36^a. The valve 39, when open, permits a blowing off of steam, but the valve 40, when open, simply opens up the pipe 36^a, so that steam may flow from the auxiliary boiler 10 into the main boiler 2. The valve 40 should be set to open under considerably less pressure than that required to open the valve 39. For instance, if the valve 40 is arranged to open the pipe 36^a when the pressure exceeds thirty pounds, then the safety valve 39 might be arranged to open under forty pounds pressure. A valve 41 is interposed in the steam pipe 36 so that the said pipe may be opened or closed, at will.

Operation: The operation summarized, is substantially as follows: A low pressure of two or three pounds, for instance, will be maintained in the main boiler 2 and we will

assume that a pressure of approximately thirty pounds is maintained in the auxiliary boiler 10. When the valve 41 is opened, steam, under ordinary high pressure will be delivered into the burning products of combustion from the fuel in the fire box, through the perforations 38 of the nozzle pipe 25. By oscillating adjustments of the said pipe 25, fine sprays of steam delivered into the products of combustion from the small perforations 38 of the nozzle pipe, may be directed where they will produce the best effects. With a strong draft in the furnace, the nozzle pipe 25 should be oscillated forward or approximately into the position indicated at the right by dotted lines in Fig. 2; for very light draft in the furnace the said nozzle pipe should be adjusted approximately into the position indicated at the left by dotted lines on Fig. 2; and for a medium draft, said nozzle pipe should be turned into a vertical position indicated by full lines in Fig. 2. The reason for these adjustments seems to be that the products of combustion, when moving rapidly, should have the steam sprays commingled therewith at a point farther back in the furnace than when moving at lower velocity. The adjustment of the nozzle pipe affords efficient means for setting the nozzle pipe in any particular furnace or fire box, or for thereafter adjusting the nozzle pipe to meet varying conditions in the draft.

Whenever there is an accumulation of steam in the auxiliary boiler 10, greater than that required to supply the discharge through the perforations 38, an increased pressure will be produced which will open up the valve 40 and permit the steam to be discharged into the main boiler 2. Thus it will be seen that this auxiliary boiler, in addition to supplying steam for the purpose stated, operates as an auxiliary steam generator working in conjunction with the main boiler. From this, it follows that when, in moderate weather, a very low fire is carried in the fire box or furnace, the entire

steam generation may be supplied from the auxiliary generator and boiler.

The result of the introduction of the steam into the products of combustion in the form of fine sprays under pressure is fully disclosed in my said companion application, referred to above. Preferably it causes complete combustion of the gases and smoke, and thereby the elimination of smoke.

What I claim is:

1. In a furnace, a steam supply pipe, a perforated nozzle pipe delivering steam to the furnace and having an offset end connected to said steam supply pipe by a swivel joint, and a rock shaft axially alined with said swivel joint and having arms connected to the said nozzle pipe for supporting and adjusting the same. 60

2. In a furnace, a steam supply pipe, a perforated nozzle pipe delivering steam to the furnace and having an offset end connected to said steam supply pipe by a swivel joint, a rock shaft axially alined with said 70 swivel joint and having arms connected to the said nozzle pipe for supporting and adjusting the same, and operating connections to said rock shaft for oscillating the same, said connections extending to the exterior of 75 the furnace.

3. In a furnace, a steam supply pipe, a perforated nozzle pipe delivering steam to the furnace and having an offset end connected to said steam supply pipe by a swivel 80 joint, a rock shaft axially alined with said swivel joint and having arms connected to the said nozzle pipe for supporting and adjusting the same, operating connections to said rock shaft for oscillating the same, said 85 connections extending to the exterior of the furnace, and an air bridge inclosing said nozzle pipe.

In testimony whereof I affix my signature in presence of two witnesses.

JOHN POMEROY.
